UNITED STATES PATENT OFFICE.

THOMAS MURPHY, OF DETROIT, MICHIGAN.

STEAM-BOILER.

SPECIFICATION forming part of Letters Patent No. 520,936, dated June 5, 1894.

Application filed February 27, 1893. Serial No. 463,901. (No model.)

To all whom it may concern:

Be it known that I, THOMAS MURPHY, a citizen of the United States, residing at Detroit, in the county of Wayne and State of Michigan, have invented certain new and useful Improvements in Steam-Boiler Furnaces, of which the following is a specification, reference being had therein to the accompanying drawings.

10 This invention relates more particularly to improvements in the construction of furnaces for such class of steam boilers which are in part or wholly composed of one or more stacks of water tubes, set either horizontally or at 15 an angle and through which the products of combustion follow an up and down course on their way to the smoke stack.

20 My invention has for its object to render the heating surface of such boilers more effective and to this end my invention consists in the peculiar arrangement of baffle plates in the circulating path of the products through the stack of tubes all as more fully herein-after described.

25 In the drawings, Figure 1 represents a vertical, longitudinal section of a well known form of sectional boiler to which my invention is applied, and Fig. 2 is a plan of the same with the upper section of the boiler removed. Fig. 3 is a detail plan of one of the blocks.

30 The boiler represented in the drawings is of that type known as the water-tube safety boiler in which A represents the horizontal steam and water-drum; B the mud drum and C a connected stack of water tubes downwardly inclined from front to rear and communicating with the drums A and B.

D is the furnace proper.

40 E is the furnace chamber in which the boiler is inclosed, and F F' are intermediate partitions or so-called baffle or division plates placed at suitable distances across the stack of tubes whereby the space between the tubes

45 is closed to compel the gases of combustion to pursue an up and down course through the stack of tubes on their way to the chimney as indicated by the arrows in dotted lines. Furnaces of this description are in extensive

50 use, but from a close observation of them I have discovered that, although the whole stack of tubes are accessibly located to the

hot products of combustion, only a portion of the stack really represents an effective heating surface. This is especially the case with 55 the front end of the stack. Here the products of combustion from the furnace taking naturally the most direct course toward the smoke stack as indicated by the dotted arrow leave the front ends of the tubes forming the 60 stack almost untouched, thus in reality a considerable portion of the front end of the stack does not form an effective heating surface and the efficiency of the boiler is thereby considerably less than it would be if this portion 65 of the stack could be made to do its duty. My invention is primarily designed to accomplish this object by a lateral extension H of the transverse baffle plate F toward the front of the stack along the top thereof. This extension I preferably make of reticulated brick 70 or tile work supported directly by the top row of tubes and provided with apertures J through which the products of combustion may pass on their way to the smoke stack. 75

I preferably use the special form of tile K, which is substantially of rectangular shape with a projection b on one edge, these tiles are placed in transverse rows with open intervals as shown whereby the tiles interlock 80 and are thereby held firmly in place. In this way no fastenings or extra supports are needed to hold the tiles in place and they can be readily removed and replaced. The weight of the tiles is but inconsiderable and being loosely 85 jointed they can freely expand and contract without damage to themselves or to the supporting tubes. It is not necessary to extend the tiles over the whole front section of the stack, it is even preferable to leave an open 90 throat K', so as to make a freer exit at this point. The function of this perforated baffle plate H is to dam up the products of combustion in the front section and thereby distribute the volume thereof, so as to entirely 95 envelop the whole front section of the boiler and make every inch of tubing therein an effective heating surface. The baffle plate H also acts to a certain extent as a reverberatory arch as it is more or less directly over the 100 hottest part of the furnace chamber.

Considering that the first baffle plate F cannot be moved any farther forward than the bridge wall, it will be seen that the loss

of heating surface in the front section of the boiler must be considerable if the products of combustion are allowed a free exit over the top of said baffle plate, even if the fuel is 5 burned directly beneath.

My invention may be with benefit applied to the other sections of the stack of tubes, thus in the next section I would place a similar baffle plate near the bottom of the stack 10 of tubes supported on the lower tier of tubes as marked in dotted lines, and in the last section similar to the front section, as also shown by a dotted line.

The advantage of placing the baffle at the 15 top of the forward section of the tubes is that the heated gases from the furnace are conducted directly and uninterruptedly into the tubes and there held or retained for a short period thus imparting its heat to the tubes 20 and water. This effect could not be had were the baffle at the base of the tubes.

I am aware that perforated baffle plates have been used at the base of the stack, in 25 connection with an imperforated plate on the top of the stack; also that an imperforated

baffle plate has been placed on top of the stack with the portion below unobstructed. In each of these cases a dead air space is formed which materially interferes with the proper and rapid heating of the stack. 30

What I claim as my invention is—

In a steam boiler furnace, the combination with the furnace chamber E, of an inclined stack of water tubes above the same, a transverse vertical baffle plate extending from the 35 bridge wall to the top of the stack, an unobstructed passage from the chamber to the top of the stack and extending from the baffle plate to the forward ends of the tubes, and a single apertured baffle plate for the space between the vertical baffle and the forward ends 40 of the tubes secured across the upper course of tubes in front of the vertical baffle plate, substantially as described.

In testimony whereof I affix my signature in 45 presence of two witnesses.

THOMAS MURPHY.
